UNITED STATES PATENT OFFICE.

DANIEL L. MAINERI, OF CANTON, OHIO, ASSIGNOR, BY MESNE ASSIGNMENTS, TO
UNITED ALLOY STEEL CORPORATION, OF CANTON, OHIO, A CORPORATION OF
NEW YORK.

METAL-SHEET-PACK-OPENING DEVICE.

1,396,768.

Specification of Letters Patent. Patented Nov. 15, 1921.

Application filed December 16, 1920. Serial No. 431,226.

To all whom it may concern:

Be it known that I, DANIEL L. MAINERI, a citizen of the United States, residing at Canton, in the county of Stark and State 5 of Ohio, have invented a new and useful Metal-Sheet-Pack-Opening Device, of which the following is a specification.

This invention relates to machines for opening packs of metallic sheets when the 10 sheets in the said pack have been caused to adhere one to the other, in the process of rolling and shearing.

The principal object of the invention is to provide means for quickly loosening one 15 of the ends of the sheets and spacing the said loosened ends one from the other.

Another object is to construct a machine that will simultaneously loosen all of the sheets in an entire pack, at one operation.

20 With these and other objects in view, the invention consists in the novel construction and arrangement of parts, hereinafter described, illustrated in the accompanying drawings, and particularly pointed out in 25 the appended claims, it being understood that various changes in the form proportions, size and minor details of construction may be made within the scope of the appended claims, without departing from the spirit 30 or sacrificing any of the advantages of the invention.

In the drawings, Figure 1, is a front elevation of my device, showing a pack of sheets in position to be opened.

35 Fig. 2 is a perspective view of the presser plate and bed plate.

Fig. 3 is an enlarged cross sectional view through the presser plate and the lower die or bed plate which coöperates therewith, the 40 ends of a pack being shown between the said presser and bed plate.

Fig. 4 is a detail view illustrating the stop for the pivoted cross bar.

Those familiar with the process of manufacturing iron or steel sheets, are well aware 45 of the difficulty which is experienced in opening a pack of sheets, after the said pack has been rolled and the edges thereof trimmed upon a shearing machine. Various 50 methods have been devised to open a pack of metal sheets in an endeavor to lessen the vast amount of human labor required to do this work, but in even the most modern and well equipped sheet mills, the packs of

sheets are still opened by laboriously flexing 55 one corner of the said pack with a man operated pair of tongs until the top sheet of the pack has loosened sufficiently to permit a sharp edged instrument to be inserted to further pry the sheet away from the balance of the pack. This method is still employed for the reason that no device prior to this time, has been constructed to satisfactorily do the work. It is obvious that the above described method is not only slow, 65 but that it requires a vast number of men to handle the output of a modern sheet mill.

My invention will not only perform the work of several men, but will accomplish the result in a small fraction of the time 70 necessary to do it by hand power since one operation of my machine will open an entire pack instantly.

At 1 is indicated a table upon which the 75 pack of sheets will be placed to be opened. Secured at either side of the said table are substantial uprights 2 and 4 which are rigidly secured at their upper ends by a cross bar 5. In each of the uprights 2 and 3 is 80 formed a horizontal bearing 6, which bearings are in horizontal alinement and are designed to receive the opposite ends of a crank shaft indicated at 7. One or more cranks shown at 8 are provided upon the crank shaft and a connecting rod 9 will be 85 attached in the ordinary manner to each of said cranks. Hingedly fastened to the lower end of each of said connecting rods is a plunger 10 which plunger is mounted to slide vertically through bearings 11 formed 90 in a cross bar 12 which is pivotally secured to the standards 2 and 4.

One extremity of the crank shaft 7 will project through one of the bearings 6 and carry thereon a gear shown at 14 which 95 gear is arranged to mesh with a comparatively small gear 15 mounted upon a shaft 16 which in turn is mounted to rotate in a bearing 17 formed adjacent the upper end of the standard 2. A tight and loose pulley 100 are mounted upon the inner end of the shaft 16 and designed to be driven by a belt 18 from any suitable source of power not shown in the drawing, and a belt shifting rod 19 designed to be moved by a pivoted lever 20, is arranged to move the belt 18 from the loose to the tight pulley when 105 the machine is to be operated.

Secured in a horizontal position to the lower extremities of the plungers 10 is a presser plate or die indicated at 20. The die 20 will be of substantially the width 5 of the pack of sheets to be opened. As shown in Fig. 2, the forward corners of the die or presser plate 20, will be flattened as at 21 for a purpose to be hereinafter set forth, and formed upon the lower side of the said presser plate is an elongated projection 22, which is of slightly less width and length than the said presser plate and is rounded as shown in Fig. 3.

In direct alinement beneath the presser plate 20 is a similarly shaped bed plate or lower die 24 which is embedded in the table top 1, the top face of the lower die or bed plate being slightly above the said table top. The bed plate will be of the exact size 15 and shape of the presser plate and will have its forward corners similarly flattened, and formed in the upper face of the said bed plate is an elongated depression of the exact proportions to receive the projection 22, if 20 the upper die were brought into contact with the said lower die.

Referring now to Fig. 4, the cross arm 12, which as previously described, is pivotally secured between the standards 2 and 4, is 30 provided with a projecting finger 25, which finger is arranged adjacent the standard 2. A pair of stops 26 and 27 carried by the said standard are located one on either side of the finger 25 and are spaced very slightly 35 therefrom. The plungers 10, sliding through the cross arm 12, are thus permitted a slight amount of "play" in descending, allowing the upper die or presser plate 20, to approach the limit of its downward travel 40 with its forward edge very slightly higher than its rear edge. It will be obvious that as the bottom of the downward stroke is reached, the connecting rods 9 and plungers 10 will be in perfect vertical alinement, thus 45 bringing the plate 20 into horizontal position, the said plate describing an arc in so doing.

The pack of sheets indicated at 30 will be placed upon the table 1 with the forward 50 edge of said pack projecting slightly beyond the forward edge of the bed plate 24 as shown in Fig. 3. The lever 20 will then be operated to shift the belt 18 on to the tight pulley, thus starting a rotation of the gears 55 14 and 15 and the crank shaft 7. A downward movement of the cranks 8 will cause the plungers 10 to lower the presser plate 20 and bring the projection 22 thereon into contact with the top sheet of the pack. Because of the peculiar shapes of the presser 60 plate 20 and the bed plate 24 and their particular points of contact upon the upper and lower sides of the pack, together with the slight rearward movement of the plate 65 20 as it comes into contact with the top of

the pack, the ends of the sheets in the said pack will begin to separate, this separation commencing first at the forward corners of the pack and in front of the flattened corners of the said presser and bed plates. As 70 the pressure from the descending plate 20 increases, the separation of the sheets will extend from the corners toward the center along the front edge of the pack until each of the sheets is entirely separated from adjacent sheets for its entire length at the 75 front edge.

The press mechanism shown in the drawings and described above, is simply illustrative of a type of mechanism for lowering 80 the presser plate, but it is obvious that any well known type of press may be used, or, a steam or compressed air cylinder with a piston working therein and having a connecting rod attached to the presser plate, 85 may be employed. It is also obvious that should a compression cylinder be used, but one plunger connecting through the presser plate will be necessary.

Having now described my invention what 90 I claim and desire to secure by Letters Patent is:—

1. In a device of the character described, an upper die flattened upon its forward corners and a lower die flattened upon its 95 forward corners and arranged in vertical alinement with said upper die.

2. In a device of the character described, a movable die of substantially the width of the pack of sheets designed to be opened, the 100 said die being flattened at its forward corners and a stationary die flattened at its forward corners and arranged in vertical alinement beneath said first die.

3. In a device of the character described, 105 a vertically movable die having flattened portions at its forward corners and a stationary die having flattened portions at its forward corners and arranged in vertical alinement beneath said vertically movable die.

4. In a device of the character described, a vertically movable die of substantially the width of the pack of sheets to be opened, flattened portions formed at the forward corners of said die, a stationary die equal to 115 said movable die in size and having similarly flattened portions at its forward corners, said stationary die being in alinement with said movable die.

5. In a device of the character described, a vertically movable die, flattened portions formed at the forward corners of said die, a projection formed upon the under face of said die, a stationary die equal in size to said movable die, a depression formed in the upper face of said stationary die, said depression being equal in size to said projection and in vertical alinement there beneath, the said flattened corners upon the said sta- 120
125
130

tionary die being in vertical alinement with the said flattened corners upon the movable die.

6. In a device of the character described
5 a vertically movable die, flattened portions formed upon the forward corners of said die, a projection formed upon the under face of the said die, a stationary die equal in size to said movable die and in alinement
10 there beneath, a depression formed in the upper face of said stationary die, said de-

pression being designed to register with the said projection carried by the movable die, flattened portions formed upon the forward corners of said stationary die similar to said 15 flattened portions formed upon the corners of said movable die and designed to register therewith.

In testimony that I claim the above, I have hereunto subscribed my name.

DANIEL L. MAINERI.
